UNITED STATES PATENT OFFICE.

CLYDE J. COLEMAN, OF NEW YORK, N. Y., ASSIGNOR TO CONRAD HUBERT, OF NEW YORK, N. Y.

STORAGE-RESERVOIR FOR EXPLOSIVE FLUIDS.

1,080,263.

Specification of Letters Patent.

Patented Dec. 2, 1913.

Application filed July 12, 1907. Serial No. 383,413.

To all whom it may concern:

Be it known that I, CLYDE J. COLEMAN, a citizen of the United States, residing in the borough of Manhattan, city of New York, 5 in the county of New York and State of New York, have invented a certain new and useful Improvement in Storage-Reservoirs for Explosive Fluids, of which the following is a specification, reference being had 10 therein to the accompanying drawings, forming a part thereof.

My invention relates to safety storage means for explosive fluids, for instance, acetylene gas, and has for its objects simplicity of construction and increased safety under various conditions, and also has as an object increased efficiency of operation in charging the storage means and in drawing off the fluid for use.

It is well known in the art that the storage of certain fluids, as for example, acetylene gas, in a condensed, compressed or liquid form is attended by extreme danger of explosion from slight predisposing causes, unless precautions are taken to provide certain safety conditions. For example, it is known that acetylene can be dissolved in acetone and stored in solution with safety up to a certain relative quantity. It is also known that acetylene and similar highly explosive fluids may be safely conserved in non-explosive condition when concentrated in a porous, cellular or interstitial mass of solid material, providing the pores, cells or interstitial spaces are not of greater dimensions than a certain critical magnitude which is the limit of immunity to explosion for a given degree of concentration or relative quantity of fluid stored.

My present invention includes improved means for utilizing both of these safety conditions in a single storage device.

My invention also includes a storage reservoir having a filler composed of solid granules of substantially uniform size so as to produce interstitial spaces of a predetermined uniform magnitude.

My invention also includes improved means to facilitate ready ingress and egress of fluid to and from the storage means and to permit free escape of the gases in case of fire.

My invention also includes certain details of construction which will appear from the following description.

The embodiment of my invention shown in the accompanying drawings will now be described, after which I will point out my invention in claims.

Figure 1 is a central longitudinal section 60 of a storage reservoir for explosive fluids. Fig. 2 is a transverse section on the line 2—2 of Fig. 1. Fig. 3 is an enlarged view showing in central longitudinal section a portion of the perforated central tube seen in Figs. 65 1 and 2. Fig. 4 shows a face view and longitudinal section, on an enlarged scale, of one of the granules or beads forming the fluid absorbing filler. Fig. 5 shows two similar views of a modified form of filler 70 bead.

In the construction shown a reservoir or container is provided comprising a metallic shell 11 filled with a great number of minute granules or beads 12. The beads 12 75 are all of the same size and preferably perforated as shown. These beads are composed of some absorbent solid, such for example, as baked porous light pipe-clay. The beads are impregnated with or allowed to 80 absorb a fluid-absorbing or fluid-dissolving liquid, for instance, acetone in limited quantities. The acetone in turn absorbs the acetylene, or other explosive fluid to be conserved. The quantity of acetone is limited 85 or restricted so that after it has been charged with the explosive fluid in solution there will still be no free liquid in the interstices between the beads, from the resulting increase in volume, but such liquid will all be retained by capillarity within the pores of the material of the beads. The perforations in the beads increase the total volume of interstitial space and also present a total larger absorptive surface both for the absorption 90 of the explosive fluid by the absorbed acetone and for giving up the explosive fluid with readiness. The beads are first tightly compacted in the reservoir and are then still more closely compressed by inserting and 100 screwing in place a valve-plug 13 carrying a pointed and tapering foraminous or perforated communicating tube 14 which is embedded among the filler beads. The tube 14 extends substantially the full length of the 105 reservoir and has perforations of slightly smaller diameter than the diameter of the beads 12, as may be seen in Figs. 3, 4 and 5, the enlargements being to the same scale. As the beads are all of the same size the 110

magnitudes of the interstitial spaces between them are substantially uniform and are predetermined by the size of beads selected, and the beads are also preferably of the same 5 shape so as to give greater uniformity to the interstitial spaces. This gives a maximum interstitial storage capacity, free acetylene being also stored in the interstitial spaces in addition to that stored in solution in the acetone. Also the magnitudes of the interstitial spaces may be exactly determined to correspond to the amount or relative quantity of acetylene it is desired to store in the interstices and so as to always be of non- 10 explosive magnitude for the quantity of explosive fluid thus stored. For example, if the beads shown in the drawing were about one-thirtieth of an inch in diameter the interstices between them and the fluid held in 15 solution by the acetone absorbed by them, would permit of the condensed storing of about one hundred and twenty-five volumes at about five hundred pounds pressure at an ordinary warm temperature. 20 It is evident that my invention provides 25 double storage in the same reservoir, one portion of explosive fluid being held in solution by the acetone which has been absorbed by the material of the beads and another portion of explosive fluid being contained in the interstitial spaces between the beads and within the perforations of the beads, such spaces being of predetermined 30 non-explosive magnitudes. 35 In my invention the fluid absorptive material (acetone) is divided into small agglomerations or segregated portions of predetermined size which store the greater part of the explosive fluid. The interstitial 40 spaces form intercommunicating passages, of non-explosive magnitudes, which serve not only for the storage of explosive fluid in a less concentrated form but also constitute passages for the ready entrance and exit 45 of the explosive fluid stored by the acetone. The explosive fluid absorbed by the acetone is held in a much more concentrated state than that contained in the interstitial spaces or passages, for example, at from one hundred and twenty-five to one hundred and 50 fifty volumes concentration, as against about thirty-five volumes in the interstices. This condition of great concentration is due to the great or intense fluid-absorptive or gas- 55 occluding effect or property of acetone, and is possible with safety both because of the protective influence of the acetone and because of the minuteness of the acetone containing pores in the solid material of the 60 beads. 65 The valve plug 13 is provided with the usual service bore forming a fluid-conduit which communicates with the bore of the communicating-tube 14. This service bore is controlled by a usual needle-valve as

shown, and inwardly from the valve is provided with a safety-vent or counter-passage controlled by a safety device shown as a usual bursting-disk. Above the valve is a service-nipple having a passage communicating with the service passage, such nipple being provided with a connector ring as shown for attachment to a service conduit 15, a portion of which is shown. 70

The modified beads illustrated in Fig. 5 could be employed with substantially equal advantages as compared with those shown in Fig. 5; in fact the two forms could be mixed together in the same container without any bad results, the principal requirement being that the beads shall be of substantially uniform predetermined sizes so as to give a predetermined uniform size of interstitial spaces. 75

It is to be noted that the communicating-tube 14 extends substantially throughout the full length of the container, and therefore a short path is provided from any part of the contained filler for the explosive fluid either in the charging operation or in drawing off the fluid for use. There is thus no practical impedance to the free flow of explosive fluid either to or from the reservoir. Another highly important function of the tube 13 is that in case of fire it provides a 95 safety exit for blowing off the gas from any point in the container. 90

The filler beads instead of being formed of a dry absorbent material, such as baked pipe-clay, as described, may be made of a gelatinized acetone compound composed, for example, of clay, a small percentage of silicate of soda, acetone, and a little gelatin; or they may be made of a powder of cocoanut-shell charcoal, kaolin or pumice stone or the like with acetone and gelatin. In this arrangement the acetone exists in the form of a jelly as an ingredient of the material of the beads instead of being taken up and held by capillarity, as in the first described arrangement. When the filler beads are formed of powdered cocoanut-shell charcoal, that material, by reason of its gas-occluding or inherent fluid absorptive and concentrative influence, will act similarly to and in conjunction with the acetone to safely conserve in a non-explosive condition large additional quantities of acetylene over that which is stored merely by compression in the interstitial spaces between the beads. 110 115

It is obvious that various modifications may be made in the construction shown and above particularly described within the principle and scope of my invention. 120

I claim:—

1. In means for safely storing explosive fluids, the combination of a reservoir and a filler therefor, the filler comprising closely compacted granules of uniform size and forming fluid-containing interstices of sub- 125 130

stantially uniform size and of non-explosive magnitudes.

2. Means for safely storing explosive fluids, comprising an elongated substantially cylindrical reservoir, a filler therefor comprising closely compacted granules of uniform size and forming fluid-containing interstices of substantially uniform size and of non-explosive magnitudes, and a perforated communicating-tube having perforations of smaller diameter than the granules and extending substantially throughout the length of the reservoir.

3. In means for safely storing explosive fluids, the combination of a reservoir, a filler therefor, the filler comprising closely compacted granules of uniform size and forming fluid-containing interstices of substantially uniform size and of non-explosive magnitudes, and a perforated communicating-tube embedded among the granules and having perforations of smaller diameter than the granules.

4. In means for safely storing explosive fluids, the combination of a reservoir, a filler for the reservoir comprising closely compacted porous granules of uniform size and forming fluid-containing interstices of substantially uniform size and of non-explosive magnitudes, and a fluid-absorbing liquid contained entirely in the pores of the granules, leaving the interstices free from such liquid.

5. In means for safely storing explosive fluids, the combination of a reservoir and a filler therefor, the filler comprising closely compacted granules of uniform size and forming fluid-containing interstices of substantially uniform size and of non-explosive magnitudes, the granules being composed of material having fluid-absorptive and fluid-concentrative influence on the explosive fluid.

6. In means for safely storing explosive fluids, the combination of a reservoir and a filler therefor, the filler comprising closely compacted granules containing charcoal of cocoanut-shell and of uniform size and forming fluid-containing interstices of substantially uniform size and of non-explosive magnitudes.

7. In means for safely storing explosive fluids, the combination of a reservoir and a

filler therefor, the filler comprising closely compacted perforated granules of uniform size and forming fluid-containing interstices of predetermined size and of non-explosive magnitudes, the granules being composed of material having fluid-absorptive and fluid-concentrative influence on the explosive fluid.

8. In means for safely storing explosive fluids, the combination of a reservoir and a filler therefor, the filler comprising closely compacted perforated granules containing charcoal of cocoanut-shell and of uniform size and forming fluid-containing interstices of predetermined size and of non-explosive magnitudes.

9. In means for safely storing explosive fluids, the combination of a reservoir, a filler for the reservoir comprising closely compacted porous granules of uniform size and forming fluid-containing interstices of substantially uniform size and of non-explosive magnitudes, the granules being composed of a substance having fluid-absorptive and fluid-concentrative influence on the explosive fluid, and a fluid-absorbing liquid contained entirely in the pores of the granules leaving the interstices free from such liquid.

10. In means for safely storing explosive fluids, the combination of a reservoir, a filler for the reservoir comprising closely compacted porous granules containing charcoal of cocoanut-shell and of uniform size and forming fluid-containing interstices of substantially uniform size and of non-explosive magnitudes, and a fluid-absorbing liquid contained entirely in the pores of the granules leaving the interstices free from such liquid.

11. In means for safely storing explosive fluids, the combination of a reservoir and a filler therefor, the filler comprising closely compacted granules containing charcoal of cocoanut-shell and of uniform size and shape and forming fluid-containing interstices of non-explosive magnitudes.

In testimony whereof I have affixed my signature in presence of two witnesses.

CLYDE J. COLEMAN.
